(57) **CLAIM**

The ornamental design for a truck saddle-mount with ball and socket, as shown and described.

DESCRIPTION

FIG. 1 is a top perspective view of a truck saddle-mount with ball and socket;

FIG. 2 is a bottom perspective view of the truck saddle-mount with ball and socket of FIG 1;

FIG. 3 is a rear elevational view thereof;

FIG. 4 is a front elevational view thereof;

FIG. 5 is a bottom plan view thereof;

FIG. 6 is a top plan view thereof;

FIG. 7 is a left side elevational view thereof; and,

FIG. 8 is a right side elevational view thereof.

The broken lines in FIGS. 3 and 5 form no part of the claimed design.
